[57] CLAIM

The ornamental design for a desk clock, as shown and
described.

DESCRIPTION

FIG. 1 is a top and right front perspective view of a
desk clock showing my new design;

FIG. 2 is a rear elevational view thereof;

FIG. 3 is a left side elevational view thereof;

FIG. 4 is a top plan view thereof as taken from line 4—4
of FIG. 3, the bottom being flat and unornamented.

FIG. 1

FIG. 2

FIG. 3

FIG. 4
